UNITED STATES PATENT OFFICE

148,807

DESIGN FOR A VEHICLE TRAILER

William B. MacDonald, Jr., Chicago, Ill.

Application January 30, 1947, Serial No. 136,521

Term of patent 3½ years

(CL. D14—3)

To all whom it may concern:

Be it known that I, William B. MacDonald, Jr., a citizen of the United States and a resident of Chicago, in the county of Cook and State of Illinois, have invented a new, original, and ornamental Design for a Vehicle Trailer, of which the following is a specification, reference being had to the accompanying drawing, forming a part thereof, and in which:

Fig. 1 is a perspective view of a vehicle trailer showing my new design;

Fig. 2 is a front elevational view of the same;

Fig. 3 is a rear elevational view of the same.

The side opposite to that shown in Fig. 1 is substantially the same as the side shown.

I claim:

The ornamental design for a vehicle trailer, as shown and described.

WM. B. MACDONALD, JR.
